(57) **CLAIM**

The ornamental design for a shaker cup and shaker cup lid set, as shown and described.

DESCRIPTION

FIG. 1 is a top perspective view of a shaker cup only, of a shaker cup and shaker cup lid set, showing our new design; FIG. 2 is a bottom perspective view thereof;

FIG. 3 is a right-side elevation view thereof, the left side being a mirror image thereof;

FIG. 4 is a front elevation view thereof, the rear elevation view being a mirror image thereof;

FIG. 5 is a top plan view thereof;

FIG. 6 is a bottom plan view thereof;

FIG. 7 is a top perspective view of a shaker cup lid only, of the shaker cup and shaker cup lid set;

FIG. 8 is a bottom perspective view thereof;

FIG. 9 is a right-side elevation view thereof, the left side being a mirror image thereof;

FIG. 10 is a front elevation view thereof, the rear elevation view being a mirror image thereof;

FIG. 11 is a top plan view thereof; and,

FIG. 12 is a bottom plan view thereof.

1 Claim, 11 Drawing Sheets
